United States Patent Office.

H. UHRY, OF NEW YORK, N. Y.

Letters Patent No. 92,670, dated July 13, 1869.

IMPROVED STAIR-ROD.

The Schedule referred to in these Letters Patent and making part of the same.

To all whom it may concern:

Be it known that I, H. UHRY, of the city of New York, in the county and State of New York, have invented certain Improvements in Stair-Rods; and I do declare that the following is a full and exact description thereof, reference being had to the accompanying drawings, in which—

Figure 1 represents the broken end of one of my improved stair-rods, seen from the front;

Figure 2 is a horizontal central section of the same;

Figure 3 represents the end of one of my improved rods when detached from the stair-case;

Figure 4 represents the fastening-button, seen from the back part thereof;

Figure 5 is a section of the same through its centre; and

Figure 6 is the screw-eye, which, with the hollow head, forms the fastening.

This invention relates to an improvement in the construction of the fastening of the stair-rods already patented by me, whereby the fastening-head is entirely detached from the rod, making both more convenient to pack, to clean, and to handle when being put up.

This invention further consists in making the front part of the head of glass, or of a translucent material, as and for the purpose fully set forth.

A is a stair-rod of any shape and design, and made of any suitable material. This rod has near both its ends, at the point where it is to be attached to the stair-case, a circular hole, F.

B is a hollow button, having a cylindrical part or projection, a, of suitable dimensions, to enter and turn freely into the hole F of the rod A.

At the bottom part of the cylindrical part a of the hollow button B, an oblong hole, f, is punched, of proper size to allow of the screw-eye T entering freely therein.

C is the top piece or front of the button B. It may be made of any desired material, but is to be slipped into the recess of the button, and there fastened by slightly bending inwardly the edges of the case.

The piece C may be made of glass, or of a semi-transparent material, and besides being ornamental, it will allow of seeing through the screw-eye, to know how the same is turned.

Disclaiming a slotted holder fastened to the rod by a lid-piece, as described in my case F, patented February 9, 1869, and numbered 86,716,

I claim, as an improvement thereon—

1. The combination of the hollow button B, screw-eye T, and rod A, constructed and arranged as shown.

2. The hollow button C, having a glass top or face, for the purpose of seeing the screw-eye when it is inserted therein.

H. UHRY. [L. S.]
